UNITED STATES PATENT OFFICE.

EMIL A. NELSON, OF DETROIT, MICHIGAN, ASSIGNOR TO HUPP-YEATS ELECTRIC CAR COMPANY, OF DETROIT, MICHIGAN, A CORPORATION OF MICHIGAN.

DESIGN FOR A BODY FOR MOTOR-VEHICLES.

41,322.

Specification for Design.

Patented Apr. 18, 1911.

Application filed January 27, 1911. Serial No. 605,139. Term of patent 14 years.

To all whom it may concern:

Be it known that I, EMIL A. NELSON, a citizen of the United States of America, residing at Detroit, in the county of Wayne and State of Michigan, have invented a certain new, original, and ornamental Design for a Body for Motor-Vehicles, of which the following is a specification, reference being had therein to the accompanying drawings, forming part thereof, in which—

Figure 1 is a perspective view of a body

for motor vehicles, showing my new design; and Fig. 2 is a rear elevation thereof.

I claim:

The ornamental design for a body for motor vehicles, as shown.

EMIL A. NELSON.

Witnesses:

W. J. BELKNAP,

JAMES P. BARRY.
